United States Patent Office

Des. 211,199
Patented May 28, 1968

211,199

HOOK

Allan G. Serle, 2586 Julian Place, Union, N.J. 07083

Filed Nov. 16, 1967, Ser. No. 9,436

Term of patent 14 years

(Cl. D41—1)

I claim:

The ornamental design for a hook, as shown and described.
